PRINTING ELEMENT ATTACHING DEVICE

Laszlo M. Stempel, Coraopolis, Pa., assignor to
The Lithograph Press Manufacturing Company, Pittsburgh, Pa., a corporation of Pennsylvania

Application November 24, 1942, Serial No. 466,714

9 Claims. (Cl. 101—415.1)

This invention relates to a transfer cylinder for applying a printed or lithographed impression to a web of paper or other material to be printed. Such cylinders are used in lithographing and printing presses, and especially in presses of the type known as offset presses in which the rubber transfer cylinder blanket bears against a cylindrical printing plate mounted on a plate cylinder disposed parallel with the transfer cylinder, as shown in Smith Patent No. 1,949,132 issued Feb. 27, 1934, on which this invention is an improvement, the blanket transferring the impression from the printing plate onto the web stock which is suitably held against the blanket by a third cylinder known as an impression cylinder.

An object of the invention is to provide means for attaching the blanket to the transfer cylinder and for taking up any stretch of the blanket which necessitates only a relatively small longitudinal opening in the transfer cylinder so that the maximum of actual printing surface is secured from a cylinder of small diameter.

A further object of the invention relates to the provision of means for easily and securely attaching one end of the blanket to the transfer cylinder, this means in the illustrated embodiment of the invention being adjustable to take up any stretch which may take place in the blanket over a period of time. For this purpose the transfer cylinder is provided with a narrow longitudinal groove into which one of a set of clamping bars is seated. Each clamping bar is provided with tapped holes, the holes in the different bars of the set being arranged at different distances from the edge of the bar. One end of the blanket is provided with a series of holes through which a plurality of securing screws pass into said tapped holes so that the end of the blanket may be held in any one of a plurality of positions depending upon which bar is used. An alternative means for taking up the stretch of the blanket is provided in connection with the bar secured to the end thereof. When the blanket is new, the edge of this bar may be seated directly against a wall of the groove in the cylinder. When the blanket has stretched, it is a feature of the invention that adjustable means is associated with the bar for taking up such stretch. For this purpose the opposite ends of the bar are provided with two shallow notches adapted to receive thin projecting lugs formed at the ends of a thin metal shim which is interposed between the edge of the bar and the wall of the groove. By providing sets of shims of different thicknesses, any stretch of the

blanket which occurs during its useful life may be readily taken up.

A further feature of the invention relates to the provision of a novel form of securing means for securing the opposite end of the blanket to the transfer cylinder and for tensioning the blanket to the proper degree so that it conforms closely to the cylindrical peripheral surface of such cylinder. In the illustrated form of the invention, the end of the blanket is clamped between two elongated bars which become seated in the longitudinal slot in the transfer cylinder, one of these bars having its opposite ends provided with projecting pins which extend into a pair of eccentric slots provided in a pair of adjustable collars mounted on the transfer cylinder shaft. By rotatably adjusting these collars, the blanket clamping bars may be drawn inwardly thereby drawing the blanket snugly against the surface of the transfer cylinder and also adjusting its tension to any desired degree.

Further objects of the invention will become apparent as the description thereof proceeds. For a better understanding of the invention, reference is made to the following description taken in connection with the accompanying drawing in which:

Fig. 1 is a transverse sectional view of a transfer cylinder embodying the invention with the blanket in operative position thereon, a portion of an impression cylinder bearing against the transfer cylinder also being shown;

Fig. 2 is a transverse sectional view of the transfer cylinder shown in Fig. 1 with one end 35 of the blanket anchored in position and the other end ready to be inserted into the cylinder;

Fig. 3 is a fragmentary side view partly in section of the transfer cylinder shown in Figs. 1 and 2, the supporting means for the cylinder also being shown;

Fig. 4 is a fragmentary view showing a portion of one end of the blanket and the means for adjustably attaching such end to the transfer cylinder, including one of the clamping bars and a shim; and

Figs. 5 and 6 are fragmentary views of other clamping bars showing different locations of the tapped holes.

The invention is illustrated in connection with a metallic transfer cylinder 1 secured to a shaft 2 which is journaled at 3 for rotation in the adjustable eccentric bearing members B of the printing or lithograph press. A pair of cylindrical gauge rollers 4 are also secured to shaft 2, these rollers serving to permit the position of the

cylinder 1 to be adjusted the proper amount with reference to the impression cylinder 5 in the manner described in the above mentioned Smith patent. A pair of collars 6 are mounted for rotation on the shaft 3, each collar being provided with an eccentric groove 7 having a radial opening 8 (Fig. 1) and one or more peripheral bores 9 adapted to receive a pin of a spanner wrench (not shown). The purpose of the collars 6 will be referred to later.

The cylinder 1 is provided throughout its entire length with a narrow longitudinally extending deep groove 10 adapted to receive the ends of a thin rubber transfer blanket 11 together with means for securing the ends of the blanket firmly in position. The illustrated means for securing one end of the blanket comprises an elongated metallic bar 12 adapted to be disposed in an extension 13 of the groove 10, the upper downwardly facing marginal wall 14 of extension 13 being inclined upwardly away from the groove proper, as shown in Figs. 1 and 2. The upper edge 15 of the bar 12 is similarly inclined to seat against the inclined wall 14 and as a result of such cam contact to be held against movement toward the groove proper, and the right hand face of the bar is provided at each end thereof with a shallow undercut or groove 16 adapted to receive a lug 17 provided on each end of and projecting from a metal shim 18 adapted to be interposed between the marginal wall 14 and the upper edge 15 of bar 12. The lugs 17 serve to hold the shim 18 in position while the bar 12 is being placed in position in the cylinder, shims 18 of various thicknesses providing a means for taking up any stretch of the blanket 11 in a manner hereinafter described. Without lugs 17, the shims would tend to slide off the upper inclined edge of the bar 12.

Another means for taking up any stretch of the blanket comprises the provision of a plurality of bars 12, 3 being illustrated (Figs. 4, 5 and 6) each having a series of tapped holes 19, 20 or 21 formed in the bar, the holes in each series being in alignment with each other, but with the holes 20 disposed at a greater distance from the edge of the bar than the holes 19, and the holes 21 at a still greater distance. The end of the blanket 11 is provided with a series of aligned holes 22 adapted to receive a plurality of securing screws 23 which are threaded into either series of holes 19, 20 or 21 in the respective bar 12 that is used.

The opposite end of blanket 11 is clamped between a narrow bar 24 and a substantially wider bar 25, the bar 24 being provided with a series of threaded holes 26 adapted to receive the screws 27 which pass through openings in the blanket 11 and bar 25. The bars 24 and 25 and screws 27 constitute a bar means with the bars 24 and 25 being portions thereof. As shown in Figs. 1 and 2, the outer portion or part 28 of bar 25 is of somewhat greater thickness than its inner portion or part and bears against both the inturned ends of the blanket 11 when the bar is in operative position, as shown in Fig. 1. Each end of bar 25 is provided with a projecting pin 29 which extends into one of the eccentric grooves 7.

In using the device one end of the blanket is attached to the bar 12 by inserting the screws 23 through the holes 22 of the blanket into the series of holes 19 in the bar having holes closest to the top of the bar. The end of the blanket, together with the bar 12 are then passed into the slot 10 into substantially the position shown in Figs. 1 and 2, so that the upper edge of the bar bears

against the inclined wall 14 of the slot 13. The other end of the blanket after being clamped between the bars 24 and 25 by the screws 27 is then wrapped around the cylinder 1. This end 5 of the blanket, together with the bars 24 and 25 are inserted in the manner shown in Fig. 2 into the groove 10 and moved radially inwards, the pins 29 entering the radial openings 8 and becoming seated in the eccentric grooves 7. The 10 blanket is then drawn into firm contact with the surface of cylinder 1 by rotating the collars 6 in an obvious manner with a spanner wrench, whereupon the pins 29 and bar 25 are forced radially inwards until the blanket is placed under the desired degree of tension. The stretch of the 15 blanket due to its repeated or prolonged use may be taken up by removing the ends of the blanket and their fastenings from the slot 10, removing the screws 23 from the threaded holes 19 and reinserting them through appropriate holes in the 20 blanket into the threaded holes 20 located farther from the top of another bar 12. The blanket is then reassembled on the cylinder in the manner above described. Any further stretch of the 25 blanket may be taken up by repeating the above process and securing the end of the blanket to another bar 12 by threading the screws 23 into the series of holes 21. Any further stretch of the 30 blanket may be taken up by inserting a suitable shim 18 between the upper edge 15 of bar 12 and the inclined wall 14 in an obvious manner. By using shims 18 of different thicknesses it will be clear that any amount of stretch of the blanket 35 may be readily taken up. Alternatively the stretch may be taken up without removing the screws 23 from the series of holes in a bar 12 by inserting shims of suitable thickness between the inclined wall 14 and the upper edge 15 of the bar. By using shims having a thickness less than the 40 distance between the series of holes 19 and 29, any small amount of stretch may be readily taken up. Whichever stretch takeup means is used at one end of the blanket, the other end thereof is forced inwardly by the bar 25 and the collars 6 with their eccentric grooves 7 which draw the 45 blanket into firm engagement with the surface of the cylinder 1 and place it under the desired tension. Fig. 1 shows the aforedescribed parts in 50 their operative position with the blanket 11 tensioned and disposed in rolling contact with the impression cylinder 5.

I have described what I believe to be the best embodiments of my invention. I do not wish, 55 however, to be confined to the embodiments shown, but what I desire to cover by Letters Patent is set forth in the appended claims.

I claim:

1. In a press cylinder having a narrow deep longitudinal groove therein, the combination with a printing element formed of flexible material, a bar secured to one end of said printing element and arranged to engage a downwardly facing wall of the groove to anchor said end of the printing element in said groove, means for anchoring the other end of the printing element in said groove and means comprising a thin shim disposed between said wall of the groove and the bar to compensate for stretch of the printing element.

2. The combination as claimed in claim 1 in which said shim is provided with lugs disposed at an angle to the main body portion thereof, said lugs being adapted to engage the bar and thereby retain the shim in position as the bar is inserted into position in the longitudinal groove.

3. The combination as claimed in claim 1 in which the bar is provided near its ends with a pair of shallow grooves and the shim is provided with lugs adapted to be seated in said shallow grooves.

4. In a press cylinder having a narrow deep longitudinal groove therein, the combination with a printing element formed of flexible material and provided along one end thereof with a series of holes, a plurality of elongated bars each adapted to be anchored in said groove and provided with a set of openings, the openings of the different sets being disposed at different distances from an edge of each bar, a plurality of securing members adapted to pass through certain of the holes in the printing element and into the set of openings in any bar, and adjustable means for forcing the other end of the printing element inwardly of said groove to thereby draw the printing element into firm engagement with the surface of the press cylinder.

5. The combination as claimed in claim 4 in which the openings in each bar are screw-threaded and the securing members consist of screws adapted for engagement with said screw-threaded openings.

6. The combination as claimed in claim 4 in which a thin shim is seated between the marginal wall of the groove and an edge of said bar, the thickness of said shim being less than the spacing between any two sets of said openings in different bars.

7. The combination of a press cylinder having a narrow deep longitudinal main groove with parallel walls and a longitudinal secondary groove in one of said walls, of a flexible printing element provided near one end with a series of holes, an elongated bar anchored in said secondary longitudinal groove and having openings therein including a set arranged in a line spaced from an edge of said bar a distance corresponding generally to the length of said printing element as attached thereto, a plurality of securing members passed through certain of the holes in said printing element and into the openings in said line of said bar, a shim placed between the upper edge of said bar and the downwardly facing upper wall of the second longitudinal groove to provide a close adjustment of said printing element, and means for anchoring the other end of said printing element in said main groove.

8. In combination, a press cylinder having a narrow, deep, longitudinal groove therein with parallel walls thereof fixedly spaced from each

other, a printing element formed of flexible material, means for anchoring one end of said printing element in said groove, a pair of elongated rigid members, one of which being wider than the other and both being adapted to be fitted into said slot, means for clamping the other end of said printing element between said rigid members, the narrow rigid member bearing against the inner face of the inturned end of the printing element and the wider rigid member bearing against the outer face of the printing element, said wider rigid member, when said members are in the slot extending outwardly beyond the outer edge of the narrow rigid member and providing a part thereof of somewhat greater thickness than the part thereof adjacent the narrow rigid member whereby upon the rigid members being forced inwardly of said groove, the inturned end adjacent the outer part of the wider rigid member will be forced over the outer edge of the narrow member and against a parallel wall of the slot thereby to conceal the narrow rigid member within the groove, filling the space between the walls of the slot and preventing thereby the inflow of dirt thereinto, and means for securing the rigid members within the cylinder groove.

9. In combination, a press cylinder having therein a narrow deep longitudinal groove with the walls thereof fixedly spaced from each other, a printing element formed of flexible material, means for anchoring one end of said printing element in said groove, bar means for anchoring the other end of said printing element in said groove comprising portions abutting both the inner and outer faces of said printing element at such other end thereof, the said outer face portion of the bar means extending depthwise of the groove to a greater distance than the inner face portion and adapted to extend outwardly beyond the outer edge of the bar means inner side portion when the bar means is located in the slot, the part of the outer face portion of the bar means extending beyond the outer edge of the inner face portion of the bar means being thicker than that part of the outer face portion immediately adjacent the inner face portion thereof thereby causing the inturned end of the printing element to be forced over the upper edge of the inner face portion of the bar means, whereby to conceal the latter portion from the outside of the groove and to fill the space within the groove and prevent the inflow of dirt thereinto and means for securing the bar means within the groove.
